UNITED STATES PATENT OFFICE.

JOSEPH L. COX, OF BATTLE CREEK, MICHIGAN, ASSIGNOR TO THE DUPLEX PRINTING PRESS COMPANY, OF SAME PLACE.

PRINTING-PRESS.

SPECIFICATION forming part of Letters Patent No. 478,503, dated July 5, 1892.

Application filed July 22, 1890. Serial No. 359,563. (No model.)

To all whom it may concern:

Be it known that I, JOSEPH L. COX, of Battle Creek, in the county of Calhoun and State of Michigan, have invented certain new and useful Improvements in Printing-Presses; and I do hereby declare that the following is a full, clear, and exact description thereof, reference being had to the accompanying drawings, and to the letters of reference marked thereon, which form part of this specification, in which—

Figures 1^a and 1^b represent a side elevation of my improved printing-press. Fig. 2 is a detail sectional view through one end of the carrier-frame cylinders, &c. Fig. 3 is a detail face view of the cam devices for operating the looping-frame. Fig. 4 is a diagram-section through the press, illustrating the course of the paper-web. Fig. 5 is a sectional detail of the inking devices. Fig. 6 is a detail.

The present invention is an improvement in printing-presses, and relates especially to web-printing presses wherein the printing is effected on a continuous web previous to severance thereof into sheets; and the present press is a combined type-bed and cylinder-press of simple and economical construction, capable of being run at a high rate of speed, and which can be employed with equally good effect either as an ordinary single-bed press or as a perfecting press for books, newspapers, &c., and wherein the register of the impressions on opposite sides of the sheets can be quickly and accurately effected without any necessary alteration or adjustment of the impression-cylinders or type beds or forms.

Another object is to avoid the use of guide and supporting tapes for directing the web through the press.

The invention consists, essentially, in a press having two type-beds arranged one above the other, whereon ordinary forms of type can be placed and used in printing, and on both beds the type rest face uppermost and point in the same direction and coacting with revolving impression-cylinders mounted in reciprocating bearings, whereby the cylinders are moved back and forth over the beds, producing a fresh impression during each stroke or movement either forward or backward.

The invention further consists in novel mechanism for conducting the web from the paper-roll above the forms on the type-beds and beneath and partly around the impression cylinder or cylinders for feeding the web continuously into and delivering it continuously from the press, yet stopping that portion of the web which is being imprinted during the time the cylinder is traveling over the form in making an impression without stopping either the feed or the delivery of the web, and for immediately feeding it forward upon the completion of the impression sufficiently to bring a fresh portion of the web into position for being imprinted by the return stroke of the impression-cylinder without lessening the tension of the web at any time.

The invention further consists in novel means for inking the forms previous to taking an impression; means for looping the web between the feed-rolls and type-bed and between the type-bed and delivery-rolls and for properly maintaining its tension, and also to permit different lengths of sheets to be printed without altering the speed or stroke of the cylinders.

The invention consists, finally, in novel supporting and operating mechanism for the impression-cylinders and form-rollers, and in certain other novel details of construction and combination of parts, as will be hereinafter more clearly described and claimed.

Referring to the drawings by letters, A designates the frame of the press, and B a shaft journaled in proper bearings in the frame near one end thereof and carrying on its outer ends crank-wheels B'. On one end of shaft B is keyed a large gear, or the periphery of wheel B' may be toothed, as at B², meshing with a small pinion b, mounted on a stub-shaft b', journaled in the side of the main frame, and a bracket attached thereto and having a pulley b³ on its extremity by which it can be driven by belting from any suitable source of power. At the opposite end of the machine and in the same plane as shaft B are guides or grooves A' A', formed in the sides of the main frame, and in these guides rest guide-lugs c c of carrier-castings C C, which support the impression-cylinder of the press, hereinafter referred to. To

carriers C are connected by transverse rods c⁵, as indicated, to constitute a kind of carriage and retain them in the guides A'. Each carrier C has an outwardly-projecting gudgeon c', to which is connected one end of a pitman E, the other end of which is secured to a wrist-pin e of the wheel B' at the same side of the machine, so that when said wheels are rotated carriers C are reciprocated horizontally back and forth in guides A'. The carriers have depending portions C², in which are formed journal-bearings for the shaft of an impression-cylinder H, which travels over the surface of a type-bed h, fixed in the frame below guides A', as indicated, and on which an ordinary type-form can be placed and secured. From each side of portions C² project in opposite directions lateral arms C³, in which are formed bearings for web-guide rollers F F, lying parallel with the cylinder, and the extremities of these arms are slotted, as at c², and in these slots are retained and journaled the gudgeons g g of inking-rollers G G, which are thus allowed a slight amount of vertical play, for a purpose hereinafter shown. Above arms C³ are short arms C⁴, in the extremities of which are formed bearings for the journals of web-guide rollers f f. As shown, a second type-bed h' is mounted in frame A directly over bed h and above guides A', so as not to interfere with the reciprocation of the carriers, and from the carriers rise upstanding portions C⁵, having laterally-projecting arms C⁶ C⁷, (corresponding to the portion C² and its arms C³ C⁴,) and in portions C⁵ is journaled the shaft of an impression-cylinder H', similar to cylinder H and traveling over bed h', and in arms C⁶ are journaled web-rollers F', and their extremities are vertically slotted to receive the journals of inking-rollers G' G', similar to rollers G.

In arms C⁷ are journaled web-guide rollers f'. The arrangement of cylinders and rollers on the upper and lower portions of the carriers is identical.

On one end of each impression-cylinder is mounted a gear H², which intermeshes with a rack H³, attached to the main frame beside the type-beds, respectively, by which a positive rotary motion is given to the cylinders as they are reciprocated back and forth over the type-beds.

At the outer or rear ends of each type-bed h h' is an ink-cylinder or distributing-roll I, mounted in proper bearings formed in or attached to the main frame, and I' I' are ink-fountains of ordinary construction mounted on the end of the main frame exterior to said rolls.

I² I² are ductor-rollers mounted in swinging arms I³, fixed on shafts W, journaled in the main frame near the rear end of each type-bed, and W' are crank-arms attached to the ends of shaft W and connected by a link-rod W², so that the shafts W will rock synchronously.

I⁴ designate upstanding fingers fixed on the outer end of the lower shaft W and adapted to be contacted by studs w on the lower rear arms of carriers C and rocked outward, thereby oscillating shafts W and throwing the ductor-rollers into contact with the fountains, and as the carriers move inward the ductors drop inward by gravity, aided by springs, if desired, and deliver ink to rolls I.

If desired to reciprocate the ductor-rollers between the fountains and ink-rolls when the carriers are at the inner end of their stroke, I propose to use fingers I⁵, pivoted to the main frame below the carrier when at the inner end of their stroke and which project into the path of and are forced backward by the studs w. The fingers are connected by link-rods I⁶ with crank-arms w' on shafts W and impart an oscillatory movement to said shafts and arms I³, and thus oscillate the ductor on both the forward and return stroke of the impression-cylinders or carriers.

I⁷ designate distributing-rollers coacting with and against rolls I I to disseminate the ink thereon.

i i are ink-rolls similar to rolls I, but mounted in the main frame in proper bearings at the inner ends of beds h h' and in same horizontal planes as rolls I I', and i' are ink-disseminating rollers coacting therewith.

i² i² designate rollers smaller than rolls I i and lying parallel therewith, but depending slightly below the same and at the sides thereof opposite the bed-plates, and i³ i³ designate endless belts running over the rollers i² at the opposite ends of the respective type-beds and contacting by their upper sides with the ink-rolls I i, respectively, and transmitting or carrying ink from rolls I to rolls i, thus enabling me to ink both rolls from a single fountain. On the ends of the inner rollers i² or their shafts are pinions i⁴, which intermesh directly with gears J on the end of a transverse shaft J', journaled in the main frame between rollers i² and shaft B, or are driven from said gears J through intermittent trains of gears mounted on stub-shafts fixed to the sides of the main frame. Gears J in turn are driven either by directly intermeshing with or by trains of gearing from gear B² on shaft B.

Above shaft J' and almost in the same plane as guides A' are arranged three calender-rolls K K' K², mounted in properly-adjustable journal-boxes secured in slots in the side of the main frame. On the shafts of these calenders are intermeshing similar pinions, by which the calenders are equally and properly speeded, and motion is imparted thereto by means of a gear K⁴, mounted on the shaft of one of the calenders and meshing with one of the gears J, as shown.

k designates the paper-roll-supporting shaft journaled in bearings in the end of the frame below and exterior to shaft B.

L designates a looping-frame formed of two uprights L', which may be connected by trans-

verse pieces, and in these uprights are journaled two compensating loop-rollers $l l$, which stand above the calender-rolls and between the same and carriers C and are adapted to form 5 compensating-loops in the web, as and for a purpose hereinafter explained. The lower ends of uprights L L are bent outwardly at right angles above shaft J' and then downwardly, and their lower vertical ends are dressed to 10 move in guides J⁶, attached to the main frame beside shaft J', and at the bends of uprights L L are outwardly-standing lugs L² L³, on which are mounted friction-rollers L³ L³, that run upon the periphery of cam-disks J³ J³, fixed on the 15 ends of shafts J' to the inside of gears J J, as shown, and by which the looping-frame is caused to reciprocate once during each revolution of shaft J'. Above the looping-frame and at the side thereof adjoining carriers C 20 is a web-guide roller M, mounted in brackets attached to vertically-upstanding nearly-central portions A² of the main frame, and vertically below roller M and below the looping-rollers is another web-guide roller M', and 25 at the outer end of the press in the same horizontal plane and parallel with roller M' is a guide-roller m', and vertically above roller m' is a guide-roller m. Rollers M m are in the same plane with each other and 30 with the guide-rollers f' f' of carriers C', and rollers M' m' are in the same plane as the guide-rollers f f of the carriers and are preferably mounted in adjustable bearings. Above the looping-frame and journaled in the upper portion of part A² of the main frame is 35 a delivery-roll O and other rollers and tapes, which coact therewith to draw the web and deliver it after impression out of the machine, or, as I prefer to arrange it, to a folding apparatus combined with the press and mounted in portion A² and above shaft B, but which I do not herein claim nor consider description thereof necessary. The roll O is driven at 40 proper speed by a train of gearing, o o from the gear K⁴.

P P designate levers connected to the ink-fountains and each other and suitable mechanism by means of which they can be shifted to cut off the supply of ink when desired, 50 and the rollers i² can be adjusted toward or from rolls I i; but these latter mechanisms do not form indispensable elements of present case and can be of any convenient construction.

55 It will be noticed that the type-beds are arranged parallel and one over or directly opposite the other, but that the type forms or plates thereon face in the same direction—i. e., the type on one bed is opposite the back 60 or bottom of the opposite bed; also, that one impression-cylinder reciprocates between the type-beds and the other reciprocates outside of the upper bed or one cylinder lies between the type-beds and one type-bed lies between 65 the cylinders, so that I can use ordinary type with perfect safety in my perfecting-press, though it is equally well adapted to printing

from plates. The course of the web is as follows: The web of paper is taken from the roll to the calenders, and fed up between the first and center calender and over the latter down between it and the third, then up over the lower compensating loop-roller l, thence down under roller M' and to and over the roller f on the adjoining side of the carriers C, thence 70 down under the roller F at the same side of the carrier, then forward beneath impression-cylinder H to and under roller F at the opposite side of the carrier, thence up over the other roller f, and then outward to the roller 75 m', under which it passes and is led up over the roller m and then back to and over the upper roller f' on the upper portion of carriers C, down under the roller F' at the same side of the carrier, inward under impression-cylinder H' and opposite roller F' and up over the other roller f' to and over roller M, and then down under the upper compensating-loop roller l and up to the delivery-rolls, as shown. The web thus makes a complete return in the 80 press, passing under both cylinders H H' and looping around the same, and the upper and lower portions of the main loop of the web lying, respectively, above the type-beds h h'. A roller P may be arranged at the rear end 85 of the press, between rollers M m, to regulate the tension of the web, if desired.

The parts should be speeded, for instance, about as follows: The calender-rolls should have a peripheral speed sufficient to draw from 90 the paper-roll and pay out enough web for an impression or one sheet for each one-half revolution of shaft B, and shaft J' should be so speeded by the gearing that it will make two revolutions for each revolution of shaft B or 95 one for each length of paper fed in by the calender-rolls, and the delivery-rolls should be so speeded that they will feed out and draw through the press exactly the amount of paper-web fed therein during a given time by 100 the calenders, so that the amount of web fed into and paid out of the press in a given time 105 will be identical. Say, for instance, that the length of form to be printed is twenty-four inches, and the amount of paper to be fed in 110 for each impression, allowing for margin, is twenty-six inches, for each half-revolution of shaft B twenty-six inches of web must be fed in by the calenders and twenty-six inches paid out by the delivery mechanism. The 115 type-bed and type, as before stated, are stationary, and for each revolution of shaft B the impression-cylinders H H' on carriers C are moved once forward and once backward over the type on beds h h', making an impression at each movement or two impressions on each side of the web for each revolution of shaft B. The portion of the web between rollers M m and M' m' must be at a standstill during the taking of an impression. 120

To more easily explain the operation of taking an impression, consider this portion of the web stopped entirely, and yet shaft B moving. The carriers C are moved in one

direction over the type on the bed, and this movement causes the impression-cylinders to press the lowest portion of the loop of web around the cylinder onto the face of the type 5 without shifting the position of the web in the least. In reality the cylinders and web-rollers moved by the carrier travel over the web and force its under surface into contact with the type, while at the same time the loop 10 or bend of the paper around or under the impression-cylinder travels with the cylinder, the guide-rollers at one side of the cylinder directing the loop of web down between the type and cylinder and the guide-rollers at the 15 opposite side of the cylinder immediately lifting the web from the type, so that when the cylinder has passed over the type the web has been imprinted and lifted clear from the type. Yet its position is unchanged, and it is 20 then necessary to move the web forward the proper distance before the return stroke of the carriers in order to make a new impression on a fresh portion of the web during such return stroke. It will be noticed that 25 the web is being all the time fed into the press by the calenders even during the taking of an impression. Hence arises the use and necessity for the looping-rollers. The cams are so constructed and mounted on shaft J' 30 that at the proper time during the movement of the carrier the looping-frame begins to rise, and the extent of stroke of such frame is calculated to be one-quarter the length of the sheet of paper paid in by the calenders. This 35 being, as supposed, twenty-six inches, the stroke of the looping-frame would be about six and one-half inches in length, and as the frame makes a return stroke for each one-half revolution of the shaft B or each movement 40 of the carriers either forward or backward over the type-beds the length of paper in the compensating loop formed by said frame would be thirteen inches. Now, saying that the looping-frame is lowered and the carrier 45 at the inner end of its stroke, the parts are so timed that the instant the impression-cylinder reaches the type the looping-frame begins to rise with such speed that all the web fed in by the calenders while the impression- 50 cylinder is on the type is taken up in forming the lower loop over roller I, so that no web is fed forward past roller M', and at the same time the upper loop formed by roller I' is paid out with equal speed, so that the 55 upper and lower loops containing an equal quantity of extra web. While the lower loop is taking up thirteen inches of web fed in by the calender-rolls the upper loop is paying off thirteen inches of web to the delivery 60 mechanism, so that no web is drawn over roller M during the passage of the impression-cylinder over the type on the bed. The moment the carrier passes the end of the bed and while it is momentarily stopped or almost 65 stopped while the wrist-pins and pitmen are passing the dead-centers the looping-frame drops and the lower loop gives off thirteen

inches of web, while the calenders pay in thirteen inches, making twenty-six inches of web which will pass over roller M', while simultaneously the upper roller I' forms a loop requiring thirteen inches of web, and at the same time an additional thirteen inches of web is drawn out by the delivery mechanism while the cylinder is off the type. It will thus 70 be seen that at one time while the main loop of the web is stationary one looping-roller takes up thirteen inches of web paid in and the other looping-roller gives out thirteen 75 inches of web previously looped on it, and that 80 when the cylinders reach the end of their stroke and are temporarily quiescent, so to speak, twenty-six inches of the web is drawn over the type-beds between rollers M' and M. In other words, the simultaneous taking up 85 and giving out of the web by the looping-rollers before and after it passes the type-beds enables the web to be fed in and delivered continuously and kept at an even tension and yet a portion of it be stopped during the taking 90 of impressions thereon. In other words, the first thirteen inches of web fed in by the calenders is taken up in forming the lower loop and is then permitted to slip off during the feeding in of the thirteen additional inches 95 of web, and thirteen plus thirteen equals twenty-six, the length of sheet, and at the same time while the thirteen inches of web first paid in is being collected by the lower loop the upper roller is paying out to the delivery mechanism the thirteen inches previously collected by it, and when the twenty-six inches of web are permitted to pass from the calenders and lower loop the delivery mechanism pays out thirteen inches of web 100 and the formation of the upper loop takes up another thirteen inches, thus preventing any accumulation of web between the lower and upper loops and preserving an equal tension on the web, though necessarily moving it 105 twice as rapidly between the upper and lower loops when it is moving at all, because the twenty-six inches of web between the loops must pass a given point in the same time that thirteen inches of web is paid in or out of the 110 press by continuous feed and delivery. 115

It will be noticed that the inking-form rollers G G' impinge against rollers I i, respectively, at the opposite limits of the stroke of the carriers, and owing to their loose mounting on the carriers they ride up and partly over and on the upper peripheries of said inking-rollers, increasing the time of contact therewith.

In order to raise rollers G G' into proper 125 position for inking the type, I prefer to mount small carrying-wheels G³ G³ on the gudgeons of the rollers, and at each end of the type-bed I attach to the frame short guides or tracks G⁴ G⁴, up which wheels G³ will run as 130 the carriers are reciprocated toward the type-bed and thus lift form-rollers G G' sufficiently to cause them to correctly strike and distribute the ink to the type on the beds. It

will be seen that the type are inked previous to each impression and that the paper is drawn from the type immediately after impression, and that when used as a perfecting press the unprinted surface of the paper is presented to the guide-rollers m', m , and f' , between the taking of the first and final impressions, and as there is no combing or drawing of the web while impressions are being taken the resultant work will be clean and clear cut. As the same amount of paper is moved forward from the lower to and over the upper type-bed at each reciprocation of the impression-cylinders, all that is necessary to make a perfect register is to adjust the position of the rollers M', m' without requiring any adjustment of the paper-feeding or delivery rolls or the impression-cylinders.

The amount or length of paper fed into the press could be varied by making the driving-gears for the shafts J , and calender-rolls, and the actuating cams for the looping-frame in interchangeable sets, calculated for different lengths of sheets in accordance with the principles before mentioned relating to the relative movements of the parts.

The ink-distributing rolls I propose to drive by belting or gearing from either of the shafts B or J' , and I also propose to drive the guide-rollers, especially M', m' , by belting or otherwise at such speed that their peripheries will travel equally with the feed and delivery of the web or slightly faster, so as to comb or coax the web from the lower press to the upper.

Having described my invention, what I claim as new, and desire to secure by Letters Patent thereon, is—

1. The combination, in a printing-press, of a pair of parallel opposite type-beds each arranged face uppermost, with an impression-cylinder for each bed, and means, substantially as described, for reciprocating said cylinders, substantially as and for the purpose set forth.

2. The combination, in a printing-press, of a pair of type-beds with a pair of reciprocating impression-cylinders coacting with said beds, only one of which cylinders moves between the beds, substantially as specified.

3. The combination of the pair of parallel type-beds arranged one above the other and having their type-bearing surfaces facing in the same direction, the pair of revolving impression-cylinders, and mechanism, substantially as described, for simultaneously reciprocating the said cylinders over the respective beds, with mechanism for feeding a continuous web of paper between one cylinder and bed and, after the first impression produced thereby, feeding it between the second cylinder and bed to produce a perfected sheet, substantially as and for the purpose set forth.

4. The combination of a type-bed and ink-rolls at the opposite ends thereof, with an ink

distributing or carrying belt adapted to deliver ink from one roll to the other, substantially as described.

5. In a printing-press, the combination of the type-bed, the ink-distributing rolls at opposite ends thereof, and the inking-fountain for supplying ink to one of said rolls, with an endless belt and its supporting-rollers for transmitting ink from one of said rolls to the other, substantially as and for the purpose specified.

6. The combination of the type-bed, the impression-cylinder mounted in movable carriers and adapted to be reciprocated over the type-bed, and the guide-rollers for directing a web of paper between the impression-cylinder and type-bed, substantially as set forth, with movable looping-rollers over which the web is looped in opposite directions before and after it passes between the impression-cylinder and bed, substantially as described.

7. The combination, with the pair of type-beds arranged parallel and both facing upwardly, of a pair of reciprocating carriers moving in guides between the type-beds and the impression-cylinders supported by said carriers and arranged to contact, respectively, with the said beds when the carriers are reciprocated, substantially as set forth.

8. The combination of the type-beds, the carriers moving in guides between said beds, and the impression-cylinders carried thereby adapted to respectively contact with the forms on said beds, with the paper-guiding rollers, whereby a web of paper can be directed between one impression-cylinder and type-bed and thence between the other cylinder and bed, for the purpose and substantially as described.

9. In a printing-press, the combination of type-beds arranged one above the other, a pair of impression-cylinders adapted to be respectively reciprocated over said beds, and inking devices for the forms on the beds, with guide-rollers arranged to direct a web of paper between the lower bed and cylinder and thence between the upper bed and cylinder, and mechanism, whereby said web is looped before it enters between the first bed and cylinder and again looped after it passes the second bed and cylinder, whereby the web can be fed into and delivered from the press continuously and yet have portions thereof stopped during the taking of an impression thereon, substantially as specified.

10. The combination, with a type-bed, of a pair of reciprocating carriers mounted in guides on the frame, an impression-cylinder journaled in said carriers, and the web-guide rollers and form-rollers mounted on the carriers at opposite sides of the impression-cylinder, substantially as described.

11. The combination of the type-bed, the revolving impression-cylinder mounted in reciprocating carriers above said bed and adapt-

will be seen that the type are inked previous to each impression and that the paper is drawn from the type immediately after impression, and that when used as a perfecting press the unprinted surface of the paper is presented

distributing or carrying belt adapted to deliver ink from one roll to the other, substantially as described.

5. In a printing-press, the combination of the type-bed, the ink-distributing rolls at op-

70

posite ends thereof and the ink-ing fountain
